(57) CLAIM

I claim the ornamental design for a plywood fastening bracket, as shown.

DESCRIPTION

FIG. 1 is a top perspective view of the plywood fastening bracket showing my new design;

FIG. 2 is a right side elevational view thereof;

FIG. 3 is a top plan view thereof;

FIG. 4 is a bottom plan view thereof;

FIG. 5 is a right end elevational view thereof; and,

FIG. 6 is a left end elevational view thereof.
